UNITED STATES PATENT OFFICE.

LEWIS J. ATWOOD, OF WATERBURY, CONNECTICUT, ASSIGNOR TO THE
PLUME & ATWOOD MANUFACTURING COMPANY, OF SAME PLACE.

DESIGN FOR A LAMP-CHIMNEY HOLDER.

SPECIFICATION forming part of Design No. 29,732, dated November 29, 1898.

Application filed November 7, 1898. Serial No. 695,796. Term of patent 7 years.

To all whom it may concern:

Be it known that I, LEWIS J. ATWOOD, a citizen of the United States, residing at Waterbury, in the county of New Haven and State of Connecticut, have invented and produced 5 a new and original Design for a Lamp-Chimney Holder, of which the following is a specification.

This design for a lamp-chimney holder is 10 represented in the accompanying drawings, in which—

Figure 1 is a side view, and Fig. 2 is a sectional plan at the line 2 2 of Fig. 1.
The top ring A and bottom ring B of the

chimney-holder have between them the flattened rods C, and the leading feature of this 15 design is the shape and appearance of the chimney-holder, resulting from the rods C being twisted.

I claim—

The design for a lamp-chimney holder substantially as described and shown.

Signed by me this 4th day of November, 1898.

L. J. ATWOOD.
